Attorney.

UNITED STATES PATENT OFFICE.

EDWARD P. OFF, OF PHILADELPHIA, PENNSYLVANIA, ASSIGNEE TO THE DENTISTS' SUPPLY COMPANY, A CORPORATION OF NEW YORK.

ARTIFICIAL TEETH.

Application filed February 18, 1926. Serial No. 88,981.

Heretofore, tooth facings for bridge work have been provided with flat sheet metal anchors baked in the vitrified tooth body and said anchors have been arranged in pairs and pointed for perforating the backing plate to which they are subsequently soldered. In practice, it has been found that flat sheet metal pointed anchors of this character frequently become crushed when being forced through the backing plate, especially where it has offered considerable resistance. It has further been necessary to employ two such sheet metal anchors to secure attachment to the backing plate over an area sufficient to insure the necessary stability in the finished bridge work.

The object of my invention is to provide a tooth facing with a stronger sheet metal anchor capable of more positively perforating a substantial backing plate without danger of being crushed and which, at the same time, will provide attachment over a sufficiently extended area to secure ample strength with the use of a single pin in the porcelain tooth structure.

My invention comprises a porcelain tooth facing provided with an anchor baked therein, said anchor formed of sheet metal bent or curved upon itself so as to provide two parts out of alignment and integrally joined at a sharp angle or on a curve, and shaped to provide a pointed anchor of considerable resistance which can be forced through a backing plate with positiveness and safety from being crushed, the additional strength being assured by the bracing effect of the angularly disposed side portions of the anchor.

My invention also comprises details of construction which, together with the above stated improvements, are fully described hereinafter and pointed out in the claims.

Referring to the drawings: Fig. 1 is a perspective view of a porcelain tooth provided with my improved anchor; Fig. 2 is a vertical section of a porcelain facing embodying my improvements in association with a backing plate; Fig. 3 is a transverse sectional view taken on line 3—3 of Fig. 2; Fig. 4 is a plan view of the sheet metal anchor blank before being bent into the angular form; Fig. 5 is a perspective view of the finished anchor before being molded

into the tooth structure; and Fig. 6 is a similar perspective view of a modified construction of the anchor.

2 is the porcelain facing or tooth body and is shown as provided with the usual flat back 3. The special anchor structure is shown at 4 and its form is best shown in Fig. 5. The special features of my improved anchor comprise the following: The anchor is stamped from thin sheet metal of platinum or suitable alloy which will not melt at the vitrifying temperature of the porcelain of the tooth body, and has the shape substantially as shown in Fig. 4 in which the upper edges 6, 6, are inclined toward each other to form the point 7 at or about the middle. The lower or embedded edge is thickened by being upset, as shown at 8, and whereby the anchor is securely attached to the porcelain tooth, as shown in Figs. 2 and 3. The plate so formed is then bent upon itself through its middle and pointed portion, and the two side portions 5, 5, thus provided being at a V-shaped angle to each other. When the angular shaped anchor is embedded in the porcelain material, the projecting portions 5, 5, thereof are at an angle to each other, and at their bent portion they provide a strong angular pointed end 7, said end projecting to a greater distance from the back 3 of the facing than the remaining side portions 5, 5. The strength of this V-shaped anchor insures the point 7 thereof being capable of perforating a relatively thick backing plate without crushing, as shown in Figs. 2 and 3. Furthermore, the angular shape of the anchor provides a means of attachment covering a large area and of a shape which prevents any displacement of the tooth relatively to the backing. Moreover, the angular form of the anchor, where it extends through the plate, provides a groove opening toward the cervical end of the tooth body and insures a stronger union with the plate and bridge (not shown) when soldered in position. A single V-shaped pin embodying my improvements will suffice for attachment to the backing plate and bridge.

In place of the V-shaped anchor being positioned in the facing, as shown in Fig. 1, it may be inverted, if so desired, or placed in any other position at the back of the

facing, as preferred, since in any position that it is placed, the rigidity of the point 7 as a perforating instrument is assured.

While I prefer to bend the sheet sharply 5 at its middle, as shown in Fig. 5, it may be more or less curved when being bent, as indicated in Fig. 6. In this case, the metal sheet is bent upon itself whereby the side portions assume a more or less angular relation to each other and the middle portion 10 projects to the greatest extent to constitute a penetrating point. The side portions 5, 5, will be united on a curve and the oblique edges 6 will also be more or less curved, and 15 where they join they will provide a relatively pointed part 7^a which, while not as sharp as the point 7 in Fig. 5, will nevertheless provide a penetrating part of great stability.

20 The anchor may be made of any suitable material capable of withstanding the temperature required to vitrify the porcelain, and while I have shown the embedded end 8 as thickened by upsetting in the course of 25 manufacture, whereby it holds firmly in the porcelain, I do not restrict myself in regard to the particular manner in which the anchor is retained in the porcelain, as any of the methods heretofore employed may be followed.

30 My invention essentially resides in the pointed construction braced by the opposite walls or side portions converging to constitute the point.

It will now be apparent that I have devised a novel and useful construction which embodies the features of advantage enumerated as desirable, and while I have in the present instance shown and described the preferred embodiment thereof which has 35 been found in practice to give satisfactory and reliable results, it is to be understood that I do not restrict myself to the details, as the same are susceptible of modification in various particulars without departing 40 from the spirit or scope of the invention.

Having now described my invention, what I claim and desire to secure by Letters Patent is:

50 1. A facing comprising a porcelain tooth body having at its back an anchor formed of sheet metal bent upon itself and secured in the tooth body so as to project substantially at right angles to the surface at said back

thereof said anchor providing a point at its bent portion and having projecting opposite 55 side portions arranged at an angle to each other to form a grooved socket opening toward the cervical end of the tooth body and having their outer edges inclined toward the point. 60

2. The invention according to claim 1, wherein further, the projecting portion of the anchor is bent in V-shape and in which the angular bend is of greater projecting length than the free ends of the side portions. 65

3. A facing comprising a porcelain tooth body provided at its back with a projecting anchor formed of sheet metal bent in V-shape and with the groove of the bend opening toward the cervical end of the body and extending therefrom at substantially right angles to its back surface. 70

4. The invention according to claim 3, wherein the grooved projection of the anchor is greatest at its angular bend and which is located most distant from the cervical end of the tooth body to form a more or less pointed portion thereat. 75

5. A facing provided at its back with a sheet metal anchor of grooved shape formed of a sheet having its projecting edges beveled toward each other and said sheet bent upon itself so as to have two side portions only and whereby the side portions assume an angular relation to each other with the groove opening in the direction of the length of the facing and the middle portion projecting to the greatest extent to constitute a penetrating point. 80

6. An anchor for a porcelain tooth formed of a flat piece of metal sheet having its outer edges beveled toward each other and said sheet bent upon itself in grooved form, whereby the side portions assume an angular relation to each other and the middle portion along the bend projects to the greatest extent to constitute a penetrating point. 85

7. The invention according to claim 6, wherein the sheet is bent abruptly into V-shape and the side portions on each side of the angular bend are flat. 90

In testimony of which invention, I hereunto set my hand.

EDWARD P. OFF.
